D. Harvey Hubbard Berlin Conn.

S. May Patent

The object here referred to in this Setting Patent and making part of the same containing a description in the words of the said Harvey Hubbard himself of his improvement in the Common Furnace Stove in the mode of generating heat and radiating heat.

To all to whom these presents shall come. Be it known that I, Harvey Hubbard of Berlin in the County of Hartford and State of Connecticut a citizen of said State and of the United States have invented a new and useful improvement in the Common Furnace Stove in the mode of generating heat and radiating heat, and that the following is a full and exact description of the construction and operation of said instrument as improved by me. This improvement consists in an addition to the Common Furnace Stove by means of which heat is radiated directly into the surrounding space more rapidly than by the Common method, and air is heated in the body of the Stove and then diffused through the flue tube warmed in an improved and economical manner. These objects are accomplished by inserting one or more Cylinder(s) or pipe(s) in the upper part of the Common furnace Stove and causing the air to circulate freely through the internal Cylinder(s) or pipe(s) inserted in said upper part. The most improved and convenient construction may be set forth.

Insert in the upper part of the Stove a Cylinder open above and closed at bottom and concentric with the upper part of the Stove and make this internal Cylinder Commun a suitable distance from the grate to give room for the fuel to burn freely in the usual quantity and manner and cause this inner Cylinder to nearly or quite the top of the Stove and make back room to the base of the upper part of the Stove that there may be sufficient space between the inner and outer Cylinder to give a free passage for the air and cause this space like that of a river bed and by this means the upper part of the Stove may be materially improved for it will radiate

8117

heat more rapidly than water will & communicate upon part or top of the upper part of the stone to the air within it. In diameter the minor Cylinder may be about three and one half inches to the width in diameter making a distance of about one and one half inches to one inch. More or less between the cylinders area in the stone proportionately smaller or larger being
to generate heat in the body of the stone and diffuse the same through the particles in a well made fluey openings day throw more air as near as practicable to the bottom of the minor Cylinder. These openings may be made by pipes communicating on the inside of the minor Cylinder and extending horizontally through the adjoining space and through the outside of the stone and carefully fitted in and thus making a free communication between the external air and the inside of the minor Cylinder. Such piping may be inserted in these openings extending downwards by the outside of the stone and terminating at any convenient point above or below or at the bottom of the stone. Such heating pipes are not essential to the improvement but useful to take the air to be heated from the lower part of the space adjoining space and to give the air greater circulation. For a a medium thick stone three pipes of about three inches in diameter each will be found suitable but the size may be varied at pleasure. For stone of other sizes the same proportion can be observed. The materials used may be Sheet or Cast iron or other suitable metal. A perforated Cover may be placed over the top of the minor Cylinder when at pleasure and such or narrow as if any may desire.

Third Claim of my improvement and for which I take effect is the addition of the minor Cylinder in the upper part of the stone with openings into said Cylinder at the bottom thereof communicating with the exterior air in the manner above described and thus increasing the quantity of heat radiated from the upper part of the stone and at the same time generating heated air in the body of the stone and diffusing it through the adjoining space in a convenient and economical manner. I claim in other parts or parts of the instrument than those above described and do not claim any right to radiate heat or generate heated air in any other cylinder separated from the top

of the stone as is done in bluestone, & a lot more. In testimony that the
above and foregoing is a true Specification of my said Improvement I
hereunto set my hand and seal at Chas Mason this twenty fifth day

of February AD 1835
